a partnership

Application August 12, 1949, Serial No. 4,446

Term of patent 14 years

(Cl. D86—10)

To all whom it may concern:

Be it known that I, Stephen F. Kayn, a citizen of the United States and a resident of New York in the county and State of New York, have invented a new, original, and ornamental Design for a Barrette, of which the following is a specification, reference being had to the accompanying drawing forming part hereof, in which:

I claim:

The ornamental design for a barrette, as shown.

STEPHEN F. KAYN.
